UNITED STATES PATENT OFFICE.

AUGUSTUS WEHLANN, OF ALDBOROUGH, ONTARIO, CANADA.

BRICK AND TILE MACHINE.

SPECIFICATION forming part of Letters Patent No. 252,636, dated January 24, 1882.

Application filed November 19, 1881. (No model.) Patented in Canada March 13, 1880.

To all whom it may concern:

Be it known that I, AUGUSTUS WEHLANN, a citizen of the Dominion of Canada, residing at Aldborough, in the county of Elgin and Province of Ontario, have invented certain new and useful Improvements in Brick and Tile Machines; and I do hereby declare that the following is a full, clear, and exact description of the same, reference being had to the annexed drawings, making a part of this specification, and to the letters and figures of reference marked thereon.

Figure 1 of the drawings is a sectional view of a machine constructed in accordance with my invention, and showing the cutting table or carriage in elevation. Fig. 2 is a top plan view of the hollow base. Fig. 3 is a horizontal section thereof, and Fig. 4 is a perspective view of the adjustable cutting table or carriage. The present invention has relation to certain new and useful improvements in brick and tile machines; and the objects thereof are to construct a machine that will prove strong and durable and effective in its operation as well as easily operated and not liable to get out of order, also insuring the perfect and effectual working of the clay and the producing of the brick or tile with comparatively little labor and trouble and with little or no waste of the clay. These several objects I attain by the construction, substantially as shown in the drawings and hereinafter described.

In the accompanying drawings, A represents an upright hollow cylinder, which may either be constructed in a single piece of metal or of two separate sections, as shown, and afterward bolted or otherwise connected together. At the top of the cylinder A is an arch or bail, a, passing diametrically across the opening in the cylinder and having its ends rigidly connected to the rim thereof. Through the arch or bail a passes a square-formed shaft, b, having connected to it above and below the arch or bail by suitable set-screws, c, collars d. The shaft b extends down and through the cylinder A, and has connected to it by set-screws e a series of knives or cutters, B. In place of being formed of cast-iron, the shaft is constructed of wrought-iron, thereby obtaining greater strength and durability.

The knives or cutters B, as will be seen, are

double instead of single, and have a square hole through their center to admit of their being slipped over the end of the shaft b, and held in position thereon by the set-screw e, as heretofore described. This enables the knives or cutters to be removed when required or adjusted on the shaft to vary the distance between them when a greater or less number is used, the set-screws being much more effective in connection with the square form of shaft than the ordinary keys now in use.

A sleeve, f, may be employed to fit within the opening in the arch or bail a, which opening is of circular form, or round, while the opening in the sleeve is square to conform to the shape of the shaft b, and a similar sleeve, g, near the lower end of the shaft, said sleeves serving as journals, thus enabling them to be removed when worn and replaced by others.

The upright cylinder A is connected in any suitable manner to a hollow base, C, into which the lower end of the shaft b projects, and is formed with a short journal, h, resting in a step, i, at the bottom of the hollow base.

The sleeve g has its bearing in a cross-piece, k, which forms a part of the top of the hollow base C, and below this sleeve the shaft b passes through a rectangular cap or plate, l. This plate covers an opening in the top of a plunger, D, located within the hollow base C, and operated by an eccentric, E, rigidly connected to the shaft b, its periphery bearing upon the faces of friction-rollers F, journaled within the plunger, as shown in Figs. 1 and 3. The plunger D forces alternately the clay through suitable molds, G, removably connected to doors H, hinged to each end of the hollow base C.

To admit of the plunger D moving backward and forward within the hollow base C, it is formed with an elongated opening, m, through which the shaft b passes, said opening being covered by the plate or cap l, as before described, so as to prevent the clay from getting into the interior of the plunger and affecting the working parts of the machine. The eccentric E, which is of cast-iron, revolves against the friction-rollers F, which causes the plunger D to have imparted to it a horizontally-reciprocating motion to force the clay out through the molds in forming the brick or tile.

The above-described means of operating the

plunger is considered of great importance, as the crank ordinarily in use for this purpose works against the side of the plunger, and the wrist of said crank necessarily wears very rapidly and lessens the quantity of clay pushed or forced out at each stroke, whereas the eccentric E gives both uniformity in motion, quantity of clay expressed, and lightness of draft.

The doors H, as will be seen, are hinged instead of being bolted, thereby facilitating the operation of changing the molds, and each door at its top has a water tap or taps, n, for the purpose of giving a sufficient supply of water to each mold in use, thereby obviating the necessity of having the base of the machine on a water-level.

The plunger D at each end is provided with two valves, o, to admit air on its receding motion, and the molds G, when found necessary, are provided with perforating-bolts p, connected to cross-bars q.

To each end of the hollow base C is connected a cutting table or carriage; but in the drawings I have simply shown one such, which is considered sufficient to describe their construction.

The table proper, as represented at I—or in other words, a carriage—is provided with suitable truck or grooved wheels, r, which ride upon tracks s, secured to a frame, K, connected in any suitable manner to the end of the hollow base C. The carriage I has connected to the sides thereof a series of horizontal rollers, t, arranged parallel with each other, which together form the bed of the carriage to receive the clay. The carriage I is provided with a pivoted stop, L, so as to prevent the clay from being pushed too far beyond the cutting-wires u, thereby rendering it unnecessary to return portions of brick or tile to the machine to be wrought over again. The wires u pass between the rollers t, and are connected at their upper end to a horizontal bar, w, and

at their lower ends to a bar, y, having its journals in the ends of the carriage I, so that it 45 can move in the arc of a circle, the ring M forming a guide for the bar w, as shown in Fig. 4.

Having now fully described my invention, what I claim as new, and desire to secure by 50 Letters Patent, is—

1. In a brick or tile machine, the square shaft b, passing through correspondingly-formed openings in journals f g, at the upper and lower ends thereof, and having removably 55 and adjustably connected to it the knives or cutters B, the same having square openings through which the shaft passes, and held thereon by set-screws e, substantially as and for the purpose set forth.

2. In a brick or tile machine, the combination, with the shaft b, carrying knives or cutters B, and eccentric E, of the plunger D, provided with friction-rollers F, and valves o, substantially as and for the purpose specified. 65

3. In a brick or tile machine, the plunger D, having air-valves o, elongated opening m, and friction-rollers F, in combination with the shaft b, carrying eccentric E, and the cap or plate l, substantially as and for the purpose 70 set forth.

4. In a brick or tile machine, the cylinder A, shaft b, knives or cutters B, eccentric E, in combination with the hollow base C, provided with hinged doors H and molds G, and the 75 plunger D, constructed as described, and having the friction-rollers F, substantially as and for the purpose specified.

In testimony that I claim the above I have hereunto subscribed my name in the presence 80 of two witnesses.

AUGUSTUS WEHLANN.
